EXPLOSION POT ELECTRIC SWITCH

Charles Cornfield Garrard, Sutton Coldfield,
Birmingham, England, assignor to The General Electric Company Limited, London, England

Application July 7, 1936, Serial No. 89,328
In Great Britain July 24, 1935

3 Claims. (Cl. 200—150)

This invention relates to explosion pot switches of the side blast type. With this form of explosion pot switch good results are obtained when heavy currents are to be interrupted by arranging that an electrode on which the arc roots upon opening of the switch is near the side outlet of the pot so that the arc experiences a strong transverse blast almost directly after formation thereof. This arrangement, however, does not prove so satisfactory when the current to be broken is small and the transverse blast weak, since the arc tends to persist for a relatively long period, and an object of the invention is the provision of electric switches which will effect rapid interruption whether the current is large or small.

According to the present improvement an explosion pot switch of the above type is provided with a plurality of explosion pots in which the explosion blasts for disrupting and extinguishing the arcs are arranged to occur in succession after all the arcs have been started at the same time in the respective pots. In this way there is provided a switch of the character indicated that is effective for breaking the circuit whether the current is large or small.

One arrangement in accordance with the invention will now be described by way of example with reference to the accompanying drawing in which Figure 1 shows diagrammatically an elevation partly in cross-section of an explosion pot switch of the side blast type embodying the invention and Figures 2 and 3 show plan views of the plates of insulating material forming the blast chambers of the explosion pots.

In the drawing, each explosion pot 1 comprises an upper substantially bell shaped part 2 of for example non-magnetic steel in which the fixed arcing contacts 3 are disposed and to the bottom of which are clamped a number of plates 4, 14 of suitable insulating material constituting an extension of the bell shaped part and forming a side outlet divided vertically into a number of passages 5. Thus alternate plates 4 are each formed with a nozzle shaped passage 5 leading from a sector 11 shaped opening through the plate to the periphery of the plate. The explosion pots are carried on bushings 6, 7 mounted on the upper wall of the switch tank. A vertically moving member 8 carries the moving contacts 9, 10 co-operating with the fixed contacts in the two explosion pots. The member 8 is operated by means, not shown, outside the switch tank. Each movable arcing contact 9 or 10 is adapted to move through the throats of the passages 5 immediately adjacent to the centres of

the circles of which the sectors form part. The intermediate plates 14 which divide the side outlet vertically are unprovided with nozzle shaped passages, but are formed with sector shaped openings 12 which register with the sector shaped openings 11 in the alternate plates 4 and which are suitably extended to allow passage of the respective movable arcing contact. The sector shaped openings form a large passage-way on the side of the movable arcing contact remote from the side outlet. The plates 4 and 14 are clamped to an inwardly extending peripheral flange 15 which is provided at the lower end of the bell shaped part 2 and which is faced with insulating material. The lower outer surface of the said part 2 is also covered with insulating material. The lower end of the pot is closed by a plate 13 formed with an aperture for the passage of the respective movable arcing contact which is of rectangular cross section. The said contact when in the closed position substantially closes the pot.

Each fixed arcing contact 3 is clamped to a boss 16 provided at the inner end of the bell shaped part on the inside thereof. The contacts comprise a pair of contacts 17, 18 adapted to engage the opposite sides of the movable contact and each comprising a tip supported on a spring finger and forced inwardly by reinforcing springs 19.

The two explosion pots are connected in series in one phase and it will be seen that in the left-hand pot the fixed arcing contacts are disposed near the upper end of the side outlet 5, whilst in the right-hand pot the fixed arcing contacts are disposed at a distance from the upper end of the side outlet.

In operation when on opening the switch the current is relatively weak and is not interrupted at the first explosion pot, i. e. the left-hand pot, the arc in the second explosion pot, i. e. the right-hand pot, is drawn to a substantial length before the movable arcing contact of that pot is withdrawn through the nozzle shaped passage of the uppermost of the alternate plates. Hence when such withdrawal opens the side of the explosion pot the arc experiences a strong transverse blast and is soon extinguished. On the other hand when on opening the switch the current is relatively strong it is rapidly interrupted at the first explosion pot, i. e. the left-hand pot.

In the arrangement shown above, contact separation in the two pots occurs simultaneously, but in an alternative arrangement the contacts in one pot may be arranged to separate before the

contacts in the other pot. Conveniently the lengths of the movable arcing contacts may be adjustable and then by adjusting the length of one of the said contacts, the separations may be caused to occur at different instants of time.

5 Moreover, it is not essential that the side outlets of the explosion pots should be divided; if desired, the side outlet to each pot may be formed as an undivided aperture in the wall of the pot.

10 Obviously the arrangement may also be applied to any usual system or arrangement of explosion pots within the scope of the invention.

I claim:

1. An explosion pot electric switch wherein the 15 explosion blasts of individual pots of a plurality of associated pots occur in succession, comprising at least two associated explosion pots, explosion blast means for the respective pots, an arcing contact mounted within each explosion pot, the 20 blast means and contact of the respective pots being relatively spaced apart different distances in the associated pots so that the explosion blasts will occur in succession and separable arcing contacts for cooperation with the contacts in the 25 respective explosion pots arranged to be simultaneously separated from the corresponding pot contacts and thereafter withdrawn through the explosion blast means of the pots so that arcs

established between the cooperating contacts are subjected to the explosion blasts in succession.

2. An explosion pot electric switch wherein the explosion blasts of individual pots of a plurality of associated pots occur in succession, comprising 5 a plurality of associated explosion pots, an explosion blast chamber for each explosion pot, an arcing contact located in each explosion pot and spaced from the corresponding blast chamber, the distance between the respective contacts and 10 chambers being different for each of the associated pots and a corresponding plurality of separable arcing contacts arranged for movement through the respective blast chambers and for cooperation with the explosion pot contacts of the 15 several pots, said separable contacts being mounted to be withdrawn from the corresponding explosion pot contacts simultaneously, the arrangement being such that arcs established between the respective contacts of the associated 20 pots are subjected to the explosion blasts in succession.

3. The explosion pot electric switch as in claim 2 wherein the contacts of the several associated explosion pots are so arranged that the circuit 25 breaks are in series.

CHARLES C. GARRARD.
